UNITED STATES PATENT OFFICE

154,300

DESIGN FOR A LETTER TRAY OR SIMILAR ARTICLE

Bert M. Morris, Los Angeles, Calif.

Application May 27, 1948, Serial No. 146,643

Term of patent 14 years

(Cl. D74—9)

To all whom it may concern:

Be it known that I, Bert M. Morris, a citizen of the United States, residing at Los Angeles, in the county of Los Angeles and State of California, have invented a new, original, and ornamental Design for a Letter Tray or Similar Article, of which the following is a specification, reference being had to the accompanying drawings, forming part thereof.

Fig. 1 is a perspective view of a letter tray or similar article, showing my new design.

Fig. 2 is a side view thereof in reduced scale, the side not shown being substantially the same as the one shown.

Fig. 3 is a front view thereof on a reduced scale.

The dominant features of my design reside in those portions shown in full lines.

I claim:

The ornamental design for a letter tray or similar article, substantially as shown and described.

BERT M. MORRIS.
